OVERJACKET FOR MOLDS

Frank W. Hamel, Detroit, Mich.

Substitute for application Serial No. 438,471,
March 24, 1930. This application August 31,
1932. Serial No. 631,255

2 Claims. (Cl. 22—112)

This invention relates to overjackets for molds, such as are engageable with a mold after removal of a flask therefrom to prevent yielding, expanding, or cracking of the mold, in its subsequent use, and is a substitute for an application filed 5 March 24, 1930, under Serial No. 438,471.

Overjackets of the described character are commonly employed to release a flask for further use after formation of a mold therein. As heretofore constructed, such overjackets have consisted of side and end walls connected substantially rigidly, and in the absence of extreme care in applying the same, there has resulted more or less relative shifting of the cope and drag portions 10 of the mold, and resultant inaccuracy in the casting. Also, rigid overjackets have proven troublesome in applying same to molds slightly varying from a rectangular contour due to flask imperfections, the rigid overjacket in such a case failing to strictly conform to the mold, and tending 15 to disturb the latter.

An object of the present invention is to provide an overjacket having separately formed walls, connected so as to afford them a slight relative movement to effect their complete conformance to any mold approximating said jacket, in shape and size.

Another object is to provide an overjacket for molds, the walls of which will be free to individually contract and expand and consequently 20 may withstand the high temperatures and extreme variations of temperature that are incident to the use of such an overjacket.

These and various other objects the invention attains by the construction hereinafter described, 25 and illustrated in the accompanying drawing:

Fig. 1 is a plan view of the improved overjacket.

Fig. 2 is a cross sectional view thereof, taken 30 upon the line 2—2 of Fig. 1.

Fig. 3 is a perspective view of a corner portion 35 of said overjacket.

Fig. 4 is a fragmentary plan view, partially in section of a corner of the overjacket showing, with 40 some exaggeration, how the walls may conform to an irregular mold.

In these views, the reference character 1 designates the separately formed side and end walls of a substantially rectangular frame, the same being 45 preferably metallic and either cast or drop forged. The walls meeting at each corner of said frame are connected by a single fastening, preferably established by a bolt 2 and nut 3, and to facilitate this connection, the walls are each flanged 50 extensively with their ends at substantially forty-five degrees to said walls, as indicated at 4, the bolts 2 engaging said flanges preferably mid-way between their upper and lower edges.

Each of said walls is formed upon its exterior 55 face with a pair of acutely divergent reinforcing

ribs 5 intersecting substantially mid-way between the ends of such wall, and there is furthermore preferably formed in each wall a plurality of perforations 6 facilitating the escape of gases and heated air from the mold, during pouring. The 65 ribs 5 of each wall preferably extend between the flanges 4 thereof. The opposite walls have a slight downward flare to correspond to that of the mold sides, the flanges 4 being relatively inclined to the main planes of the walls 1 to establish such flare. The nuts 3 may be tightened or loosened upon the 70 bolts 2 to afford such play between the meeting walls as may be required to fully conform said walls to a given mold.

By thus providing for a limited play between the meeting walls of an overjacket, the latter may 75 adjust itself accurately to slight variations in different molds, and the percentage of loss from defective castings due to disturbance of the mold by the overjacket may be greatly reduced.

The construction avoids necessity for machine 80 operations, excepting the simple one of drilling the flanges 4 to take the bolts 2. The holes receiving said bolts are sufficiently oversized to permit considerable angular play between the joined 85 walls.

While it is apparent that the invention is well 90 calculated to adequately fulfill the objects and advantages primarily stated, it is to be understood that the invention is susceptible to variation, modification and change within the spirit and scope 95 of the subjoined claims.

What I claim is:

1. An overjacket for molds comprising opposed side and opposed end walls forming a substantially 95 rectangular frame, each of said walls being integrally formed with flanges outwardly projecting in a substantially diagonal relation to said rectangular frame, the opposed walls being downwardly divergent and said flanges being substantially vertical, said flanges having substantially the full height of said walls, the adjacent flanges of adjoining walls being formed with registered openings, and a connecting member mounted loosely in said openings of each pair of adjacent flanges, maintaining the adjacent relation of said flanges and affording the connected walls adequate relative play to adapt the jacket to conform 100 itself to different molds.

2. In an overjacket for molds, as defined by 110 claim 1, means associated with said connecting members for varying the size of the rectangular frame.

FRANK W. HAMEL.
